WHITEHEAD & KALES, OF DETROIT, MICHIGAN, A CORPORATION OF MICHIGAN.

OIL BURNER.

Application filed June 1, 1926. Serial No. 113,967.

The invention relates to oil burners and particularly to improvements in the design thereof having particular bearing upon the efficiency and simplicity of the device and consequently its commercial acceptability.

Heretofore oil burners of this character have been objectionable in various respects. One of the most prevalent objections in the commercial types of oil burners now in vogue is that they are inefficient because they produce a yellow flame rather than a blue or colorless flame which is indicative of proper fuel proportions. A yellow flame is a result of either too much air or too much fuel and as the use of too much fuel is not only uneconomical but results in a carbon deposit, which after continued use causes considerable trouble, the majority of the heaters now in use supply too much air. While this character of inefficient mixture is not as disadvantageous as a mixture including too much fuel still from a standpoint of heat intensity the flame resulting from a mixture including too much air is obviously quite inefficient.

Furthermore the present types of fuel burners in many instances prove to be objectionable because of the noise incident to the operation thereof and furthermore to the complexity of the mechanism thereof. This latter objection is of extreme importance because burners involving complicated mechanism are not only expensive to manufacture but get out of order quickly and are difficult to repair.

It is therefore one of the primary objects of this invention to provide an oil burner of an extremely simple construction and with a minimum number of moving parts. Hence a burner in accordance with this invention may be economically manufactured and used.

Another object of this invention is to produce an oil burner in which an efficient fuel mixture is assured under all operating conditions and one in which a blue or colorless flame is obtained, this type of flame being the result of a fuel mixture of the correct proportions.

Many of the more or less serious objections to the present commercial types of oil burners are eliminated in this present invention by a construction which insures a separation of the oxygen and fuel vapors

except at the combustion point whereby liability of internal explosions or flarebacks is eliminated.

The efficiency of the present oil burner is partly the result of the ejector effects produced by the heater whereby a proper intermingling or mixing of the air and fuel vapors is constantly assured, the extent of which is obviously dependent upon the proficiency of the ejector which in turn is dependent on the extent to which the burner is being operated. Thus after the proper proportion of fuel and air has once been determined this relation and consequently the efficiency of the mixture will thereafter be maintained throughout the operation of the burner.

By means of the ejector used in connection with the present invention, the flame may be directed as desired, within certain limits, so as to adapt the burner to installation in various types of furnaces and boilers.

Practically all of the oil burners now designed and used claim as an advantage thereof the possibility of the use of heavy and relatively inexpensive oil as the fuel. The use of this heavy poor grade fuel involves certain disadvantages which the manufacturers of burners heretofore have attempted, with little success, to overcome. This low grade of fuel when heated or incompletely burned leaves a considerable amount of carbon deposit which not only causes smoke but also clogs or otherwise incapacitates the conduits, openings and other parts of the burner. Much of this trouble results from the fact that the fuel oil in being conducted to the burner is subjected to the heat thereof before being deposited free of its conduit into the combustion or fuel chamber of the burner. Therefore, this present invention contemplates means whereby the fuel oil is maintained at a relatively low even temperature until such time as it is deposited into the oil receptacle of the burner.

Another structural feature of the present invention which is partly responsible for the efficiency thereof consists in that arrangement of several of the parts which permits of and functions to draw and mix with the oil vapors some of the semi or partially burned gases whereby the efficiency of the

combustible mixture is materially enhanced.

Various other objects, advantages, and novel details of construction of the invention will be made more apparent as this description proceeds, especially when considered in connection with the accompanying drawing wherein one illustrative embodiment of an oil burner constructed in accordance with this invention is illustrated in 10 longitudinal vertical section, certain parts, however, being left in elevation.

Referring now particularly to the drawing wherein like reference characters indicate like parts, it will be noted that there is 15 illustrated a pot-like housing or receptacle 10 provided at one side thereof with a laterally extending tubular extension 11, herein shown as formed integrally with the container 10. The receptacle portion 10 of the 20 burner is lined with refractory material 12, a laterally extending ledge or support 13 being provided adjacent the upper edge of the housing 10 for supporting a refractory ring 14 whose particular purpose, in the 25 present form of construction, is to deflect and direct upwardly the flames which are directed thereagainst by the ejector nozzles of the burner yet to be referred to.

The reference character 15 indicates generally the burner nozzle which is preferably of a circular or annular configuration and consists essentially of an inner sleeve-like portion 16 provided at one side with a tubular extension 17 which extends into and is 30 supported with tubular extension 11 of the burner receptacle 10. These parts may be secured against displacement as for instance by means of one or more fastening elements 18. Spaced from the inner element 16 is 35 a tubular sleeve-like element 19 spaced substantially uniformly radially of the inner element 16 and supported thereupon by engagement with the tubular extension 17 and also by means of one or more lugs 20 resting upon lugs 21 projecting from the inner element 16. A mushroom-shaped cover 22 engages, through the intermediary of a plurality of lugs 23 with the out-turned peripheral portion 24 of the outer element 19. This 40 cover 22 is also formed with a radially directed peripheral edge portion 25 which is spaced throughout, except at those points where lugs 23 are provided, from the peripheral edge 24 of the element 19. Thus an 45 annular or circular ejector nozzle 26 is provided. Associated with the upper peripheral edge 27 of the inner element 16 is a cover element 28 whose radially directed peripheral edge portion 29 is spaced from 50 the peripheral edge portion 27 to produce an annular ejector nozzle 30. The dimensions of this ejector nozzle 30 may be regulated and the cover element 28 supported by 55 means of a set screw 31 connected to the cover element 28 and threadedly engaging

the cover element 22. The cover element 22 is provided with one or more apertures 32 for a purpose which will appear more fully hereinafter. In the description of the operation of the burner, the ejector nozzle 70 30 will be termed the primary ejector and the nozzle 26 a secondary ejector.

The lower end of the inner element 16 is closed but is provided with a pair of apertures 33 and 34 which are respectively the fuel opening and the pilot burner opening. Arranged within the element 16 is a fitting or casting 35 which rests upon the bottom of the element 16 and is provided with nipple-like projections 36 which enter the openings 33 and 34 and position the fitting 35 with respect thereto. This fitting is provided with a passageway 37 for the pilot burner gas which is connected to a supply pipe or conduit 38 which extends longitudinally through the tubular extensions 17 and 11. The conduit 38 threadedly engages the fitting 35 as indicated at 39. The fitting is also provided with a passageway 40 for the fuel oil, this passageway communicating through the nipple 36 with the opening 33. The fuel supply conduit 41 has a threaded connection 42 with the fitting 35. Surrounding the fuel oil supply conduit 41 is a pipe or conduit 43 which communicates with the chamber 44 formed in the fitting 35. This conduit 43 has a threaded connection as at 45 with the fitting 35. The conduit 43 surrounds the conduit 41 throughout its length from the point of connection with the fitting 35 to a point spaced from the burner and is adapted to provide an annular space 46 for a cooling fluid for the fuel oil supply conduit 41 and the contents thereof. The cooling fluid space 44 of the fitting 35 is 105 of course in communication with the space 46.

The pipes 38, 41 and 43 all extend through the tubular extension 17 and 11 and also through a tubular casing 47 which is flanged 110 at its ends as indicated at 48 for attachment to a corresponding flange 49 formed on the extension 11. A supply pipe for the gas pilot burner may be connected to the pipe 38 at the point indicated at 50 while the cooling fluid supply pipe will be connected to the pipe 43 at the point indicated at 51. The reference character 52 indicates the fuel oil supply pipe which extends from a supply tank or other source of supply and is connected to the conduit 41, as for instance by means of a coupling indicated at 53. It will be noted that a space 54 is provided between the pipes contained within the housing 47 which space may communicate at the end 125 with a motor driven blower 55 for supplying air under pressure through housing 47 and the tubular extensions 11 and 17 to the spaces 56 interiorly of the inner element 16.

In operation fuel oil will be supplied 130

through pipe 41 and fitting 35 and through aperture 33 and will be deposited in the shallow depression 57 in the bottom of the body of the heater. At the commencement of the 5 operation of the burner the flame from the pilot burner which issues from the opening 34 will ignite the oil and thus create sufficient heat so as to effect the automatic vaporization of the fuel oil as is customary in 10 heaters of this character.

Assuming the heater to be in use and consequently the refractory material and the other parts of the heater to be at a high 15 temperature the oil deposited into the bottom of the heater will be instantly vaporized. The air in the chamber 56 in the inner element 16 will issue from the primary ejector 30 and will create a vacuum or relatively lower pressure in the annular space 58. 20 This will draw upwardly into this annular space vapor from the oil in the pool 57, these vapors being satisfactorily directed into the annular space 58 because of the outwardly flaring lower end 59 of the outer sleeve-like 25 member 19. The air issuing from the ejector nozzle 30 will mix with the vapor drawn upwardly through the annular space 58 and this mixed vapor and air will then issue from the secondary ejector 26. There will 30 be a partial ignition of the combustible mixture on an annular line spaced from the ejector nozzle 30 but owing to the force of the air the complete ignition will not take place until the mixture issues from the ejector 35 nozzle 26. This secondary ejector directs the flame laterally against the refractory ring 14 which in turn deflects the flames annularly upwardly and outwardly.

The air issuing from the primary ejector 40 30 into the annular space 58 induces therein a relatively lower pressure which is herein referred to as a vacuum. The ejector functions additionally to produce a pumping or impelling effect by reason of the fact that 45 the molecules of the air strike the molecules of the fuel and impel or force the same outward through the secondary ejector. Thus in addition to the relatively lower pressure attained which assists in drawing the fuel to 50 a point adjacent the primary ejector the primary ejector acts to impel the fuel from this point outward through the secondary ejector.

Liability of pre-ignition is avoided by 55 this construction because there is not sufficient oxygen in the fuel vapor to support ignition until this fuel vapor arrives adjacent the ejector nozzle 30. Consequently the first point at which ignition of the fuel takes 60 place is on the annular line spaced from the ejector nozzle 30, complete ignition taking place after the mixture issues from the secondary ejector 26 as aforescribed. It should be noted that the air issues directly 65 through the column of fuel vapor thus in-

suring a complete intermingling of the air and fuel and furthermore the quantity of the fuel vapor and partially burned gases drawn upwardly through the passage 58 is in direct relation to and dependent upon the 70 amount of air issuing from the primary ejector nozzle so that there is a tendency to maintain the proper relationship between the fuel and air under all working conditions of the burner. 75

It should be understood that the ratio of fuel and air is first determined by properly selecting the size of the blower and consequently the amount of air supplied to the burner and also by properly regulating the 80 amount of oil supply to the burner. With the ratio of these two constituents initially fixed the quantity of fuel vapor and partially burned gases drawn through the burner by the vacuum created by the air ejector 85 bears a fixed relationship to the quantity of air ejected.

The primary ejector 30, by reason of the vacuum which it creates, will draw a certain amount of burned gases from the space 90 above the cover plate 22 through the apertures 32 thereof which burned gases will mix with the air and oil vapor to improve the combustion thereof. Furthermore the vacuum created by this primary ejector in 95 the annular space 58 tends to draw some of the semi-burned gases present in the annular space between the outer element 19 and the annular refractory wall, the passage of these semi-burned gases being indicated by 100 the arrows A. These semi-burned gases will be drawn downwardly then upwardly through the annular space 58 and will mix 105 with the oil vapor to increase the efficiency of the final combustible mixture. 110

In connection with the operation of the ejectors and their bearing upon the efficiency of this burner it should be noted that the primary ejector delivers the air at the point where it is desired the combustion start and furthermore that this air is delivered in a thin flat stream. As was heretofore mentioned the width of the ejector nozzle opening 30 may be regulated by means of the set screw 31. Furthermore the stream of air 115 issuing from the primary ejector creates a vacuum which draws the oil vapor to the proper place, that is to a point between the primary and secondary ejectors where the issuing stream of air passes through the oil vapor thus insuring a complete intermingling and consequently an efficient mixture. It is also apparent that the vacuum thus created draws in some partially burned and 120 completely burned gases from above and below which mix with the oil vapor on the way to the ejector nozzle. Obviously by reason of the shape of the secondary ejector the flame issues therefrom in a flat annular sheet and is directed against the refractory 125 130

ring 14 where it is deflected to the sides of the furnace or boiler. It will be apparent that the direction in which the flame issues may be easily altered by properly changing 5 the contour of the secondary ejector.

By maintaining a constant supply of some cooling medium, such for instance as water, in the annular chamber 46 which surrounds the oil supply conduit 41, the temperature of 10 this oil will be maintained sufficiently low to prevent decomposition thereof and consequently eliminate the disastrous carbon or tarry deposits which would otherwise result where low grade fuel oils are subjected 15 to high temperatures.

Obviously the pilot burner as well as the conduit thereto may be arranged differently with respect to the remaining parts if this is found desirable or may be eliminated entirely, as the fuel can be ignited initially 20 in various other manners such for instance as by means of an electric pilot.

While one illustrative embodiment of the invention has been shown and described 25 herein somewhat in detail, it will be readily apparent that the principles of this invention are capable of expression in various other forms and accordingly the invention should not be considered as limited in any 30 respect to the structural details and arrangements herein shown. Reservation is therefore made to make such changes in the essential and all of the non-essential details as may come within the purview of the 35 accompanying claims.

What we claim as our invention is:

1. In an oil burner, a chambered member 40 connected to a source of air supply and provided with an ejector nozzle, a casing surrounding said member in spaced relation and provided with an ejector nozzle in substantial alignment with said first mentioned nozzle, a fuel oil pool beneath said above mentioned members and means for supplying 45 fuel oil thereto, said casing being open in the area of said pool for conducting the vapors therefrom to a point adjacent said first mentioned ejector whereby said air and fuel vapors are mixed and ejected through 50 said second mentioned ejector.

2. In an oil burner, a body portion formed of refractory material or the like and adapted to contain a quantity of fuel oil, means 55 for supplying fuel oil thereto, a chambered element connected to a source of air supply and provided with an ejector nozzle, a casing surrounding said element in spaced relation thereto and constituting a fuel vapor directing means, said casing being provided 60 with an ejector nozzle adjacent said first mentioned ejector nozzle and with an open end adjacent said quantity of fuel oil whereby the vapor from said fuel will be drawn through said passage by the vacuum resulting from said first mentioned ejector to

cause this fuel vapor to mix with the said air whereupon the resulting combustible mixture is ejected from said second mentioned ejector.

3. In an oil burner, a substantially pan-like base of refractory material or the like, a chambered element provided with a circular ejector nozzle and with a fuel oil supply opening for supplying fuel to a pool in said pan-like base and with means of ignition, means for supplying fuel to said fuel oil opening, a casing surrounding said element in spaced relation thereto, said casing being open to receive the fuel vapor and gas and provided with other openings for receiving heated or burned gases, said casing being provided with a circular ejector nozzle in substantial alignment with said first mentioned ejector, and means for supplying air to the interior of said chambered element 85 whereby said air will issue from said first mentioned ejector and create a vacuum in the space between said element and spaced casing to thereby draw fuel vapor and gas to a point adjacent said ejector, whereby 90 said air, gas and fuel vapor are mixed and ejected from said second mentioned ejector in the form of a combustible mixture.

4. In an oil burner, a substantially pan-like base of refractory material or the like, 95 a chambered element provided with a circular ejector nozzle and with a fuel oil supply opening for supplying fuel to a pool in said pan-like base and with a means of ignition, means for supplying fuel to said fuel oil opening, a casing surrounding said element in spaced relation thereto, said casing being open to receive the vapor from said pool and provided with openings for receiving heated or burned gases, said casing 100 being provided with a circular ejector nozzle in substantial alignment with said first mentioned ejector, and means for supplying air to the interior of said chambered element whereby said air will issue from said first 105 mentioned ejector and create a vacuum in the space between said element and spaced casing to thereby draw fuel vapor and gas to a point adjacent said ejector, whereby 110 said air, gas and fuel vapor are mixed and ejected from said second mentioned ejector in the form of a combustible mixture.

5. In an oil burner, a substantially pan-like base of refractory material or the like, a chambered element provided adjacent its 120 top with a circular ejector nozzle and adjacent its bottom with a fuel oil supply opening for supplying fuel to a pool in said pan-like base and with a means of ignition, means for supplying fuel to said fuel oil 125 opening, a casing surrounding said element in spaced relation thereto, said casing being open at its lower end to receive the vapor from said pool and provided with openings adjacent its top for receiving heated or 130

burned gases, said casing being provided with a circular ejector nozzle in substantial alignment with said first mentioned ejector, means for adjusting said first mentioned 5 ejector nozzle and means for supplying air to the interior of said chambered element whereby said air will issue from said first mentioned ejector and create a vacuum in the space between said element and spaced

casing to thereby draw fuel vapor to a point 10 adjacent said ejector, whereby said air and fuel vapor are mixed and ejected from said second mentioned ejector in a thin sheet in the form of a combustible mixture.

In testimony whereof we affix our sig- 15 natures.

HAROLD A. GREENWALD.
JOHN D. HOWE.
